No. 623,662.

Patented Apr. 25, 1899.

J. H. GOSS.

FOOT PUMP.

(Application filed Nov. 16, 1898.)

(No Model.)

UNITED STATES PATENT OFFICE.

JOHN H. GOSS, OF WATERBURY, CONNECTICUT, ASSIGNOR TO THE SCOVILL MANUFACTURING COMPANY, OF SAME PLACE.

FOOT-PUMP.

SPECIFICATION forming part of Letters Patent No. 623,662, dated April 25, 1899.

Application filed November 16, 1898. Serial No. 696,620. (No model.)

To all whom it may concern:

Be it known that I, JOHN H. GOSS, a citizen of the United States, residing at Waterbury, in the county of New Haven and State of Connecticut, have invented a certain new and useful Improvement in Foot-Pumps, of which the following is a full, clear, and exact description.

This invention relates to air-pumps, and more especially to that class of air-pumps which are used for inflating pneumatic tires and are known as "foot-pumps."

In my invention I employ a novel cap upon the discharge end of the barrel or body of the pump, and this said cap has attached to it the stirrup, and it is also provided with a nipple for the application of the flexible tubing for conveying away the air. The pump-plunger is provided with a rigid (preferably steel) cup, which aids in holding the leather in place and also serves to limit the downward stroke of the plunger. The plunger-rod is provided with a knurled bead to form a shoulder for the metal washer of the piston and a seat to hold the buffer-spring in place.

In the accompanying drawings, illustrating my invention, in the several figures of which like parts are similarly designated, Figure 1 is a perspective view of the complete pump. Fig. 2 is a longitudinal section of the lower end of the pump. Fig. 3 is a perspective view, partly broken away, of the plunger-cup. Fig. 4 is a cross-section of the cap, taken substantially at right angles to the view Fig. 2. Fig. 5 is a perspective view of the cap detached. Fig. 6 is a top plan view of the cap and stirrup detached. Fig. 7 is an elevation of the inner end of the plunger-rod.

The body or barrel *a*, the stirrup or foot-rest *b*, the plunger-rod *c*, modified in construction, as presently described, and its handle *d* and buffer-spring *e* may be otherwise of usual construction.

The cap *f* for closing the lower end of the barrel or body of the pump is made with a flange *f'*, which is internally screw-threaded to engage an external screw-thread on the barrel or body of the pump, and it is further made with a hollow bead *f''*, projecting outwardly beyond the perimeter of the flange *f'*.

f''' is a flange at the base of the hollow bead,

which flange, in connection with the said bead, receives the packing-ring *f⁴*. (See Fig. 2.) The cap terminates in an angular or other shaped chamber *f⁵*, and this chamber is provided, preferably, with an inwardly-projecting nipple *f⁶*, which is internally screw-threaded to receive the coupling of the discharge-tube *A*.

The stirrup *b* has its upper ends arranged upon the sides of the chamber *f⁵* of the cap *f* and is secured thereto by a rivet *g*, passed transversely through holes in the said ends of the stirrup and holes *h* in the sides of the chamber *f⁵*; and these ends of the stirrup may be further secured to the sides of the chamber of the cap *f* by solder or other medium in order to make a perfectly tight and rigid joint therewith. From this construction it is obvious the stirrup and the cap *f* are rigidly secured and movable one with the other and that by this construction a ready means is afforded for assembling and detaching the parts of the pump.

The pump plunger or piston *i* may be composed of the usual metal washer *i'* and leather cup *i''*, and beneath this leather cup is a rigid metal cup *k*, which is secured to the rod *e* by means of a nut *l*, secured upon a screw-threaded projection of the rod *e*. This metal cup *k*, preferably of steel, is longer than the leather cup and comes into contact with the packing-ring *f⁴*, and thus prevents the rod *e* from striking the rivet *g* in the descent of the plunger, and so preserves said rivet from distortion and the consequent loosening of the stirrup.

The cap *f* may be struck up in dies or otherwise formed of sheet metal very expeditiously and cheaply, as also may be the steel cup *k*.

While I prefer to make a screw-thread connection of the cap *f* with the body or barrel of the pump, I do not limit my invention to such connection.

A bead *c'* is knurled into the plunger-rod and forms a seat for the steel washer *i* and at the same time affords a place in which to fasten the buffer-spring *e*, and thus keep it from rattling up and down. This construction is cheaper than milling a shoulder on the end of the plunger-rod, which is the usual construc-

tion. The knurled bead is shown as a groove having its opposite edges thrown out by displacement of the metal of the rod. The lower coil or coils of the buffer-spring engages or engage 5 the bead, and thus said spring is held in placee on the rod.

By the construction of the various parts described a very efficient, strong, and durable foot-pump may be produced at comparatively 10 small first cost.

What I claim is—

1. A foot-pump, having a body or barrel, a cap therefor constructed with a screw-threaded flange to engage a complemental screw-thread 15 on the body or barrel, said cap terminating in an exit-chamber, a stirrup having its ends applied to the sides of such chamber and a rivet passed through such ends and the cap, to rigidly unite the cap and stirrup, substantially 20 as described.

2. A foot-pump, having a body or barrel, a cap therefor constructed with a screw-threaded flange to engage a complemental screw-thread 25 on the body or barrel, said cap terminating in an exit-chamber, a stirrup having its ends applied to the sides of the chamber and rigidly united with the cap by solder and a rivet, substantially as described.

3. A foot-pump, having a screw-cap for closing 30 the bottom of the body or barrel, and constructed with a hollow bead, a washer therein and an exit-chamber, and a stirrup applied to the sides of said chamber and rigidly secured to the cap by means of a rivet passed through 35 the said stirrup and chamber, substantially as described.

4. A foot-pump, having a body or barrel, a cap struck up from sheet metal and constructed with a screw-threaded flange to engage a complemental screw-thread on the body or 40 barrel, an exit-chamber having an outlet-nipple, a stirrup fitted to the sides of such chamber and secured to the cap by a rivet, substantially as described.

5. In a foot-pump, the combination of a 45 body or barrel, a screw-cap for closing its lower end, a stirrup riveted to said screw-cap, and a plunger having a metal cup projecting below its lower end and adapted to come in contact with the screw-cap above said rivet to 50 clear the descending plunger from said rivet, substantially as described.

6. In a pump, a body or barrel having an exit-chamber, and a plunger having an inverted metal cup applied beneath the packing and serving to arrest the movement of the plunger with relation to the exit-chamber, substantially 55 as described.

7. In a pump, the combination with the piston or plunger having a metal washer, of 60 a buffer-spring, and a plunger-rod having a knurled bead forming a seat for the washer and a fastening for the buffer-spring, substantially as described.

In testimony whereof I have hereunto set 65 my hand this 14th day of November, A. D. 1898.

JOHN H. GOSS.

Witnesses:

EDWARD O. GOSS,
GEO. F. HODGES.
